PARACHUTE RELEASE SAFETY DEVICE

Filed June 22, 1929

UNITED STATES PATENT OFFICE

BENJAMIN F. TOFFLEMIRE, OF BERKELEY, CALIFORNIA

PARACHUTE-RELEASE SAFETY DEVICE

Application filed June 22, 1930. Serial No. 372,865.

The present invention relates to improvements in release mechanism for parachutes and its principal object is to provide a release mechanism for a parachute that automatically becomes active a few seconds after the person carrying the parachute has jumped from the airplane.

A further object of the invention is to provide a release mechanism of the character described which does not require any action on the part of the person carrying the same, except that of jumping from the airplane.

Another object of the invention is to provide, in combination with such automatic release mechanism, means for delaying the release for a few seconds until the person carrying the parachute is absolutely clear of the airplane.

Further objects and advantages of my invention will appear as the specification proceeds.

The preferred form of my invention is illustrated in the accompanying drawing, in which

Figure 1 shows my release mechanism in perspective view;

Figure 2 shows a vertical section therethrough, parallel to the front wall of Figure 1;

Figure 3, a horizontal section taken along line 3—3 of Figure 2;

Figure 4, a horizontal section taken along line 4—4 of Figure 1; and

Figure 5, an assembly view showing my release mechanism in place on a parachute.

While I have shown only the preferred form of the invention, I wish to have it understood that various changes or modifications may be made within the scope of the claims hereto attached without departing from the spirit of the invention.

In its preferred form, my release mechanism comprises a casing 1 adapted for fastening to a parachute 2 in the manner indicated in Figure 5. Parachutes, as at present constructed, are released by a pull on a rip cord, indicated at 3, and at the present time, it is customary to let the person using the parachute pull the rip cord a few seconds after he has jumped from the airplane. It

is a well-known fact, however, that in many instances, the person using the parachute is too excited to pull the rip cord at the proper time and either fails to release the parachute altogether or releases it too soon, which causes the parachute to become tangled up in the airplane itself.

The object of the present invention is to cause the parachute to be released automatically without any action on the part of the person using the same, and for this purpose, the rip cord 3 is fastened to the end of a rod 4 retractably mounted in the front wall 5 of the casing, the rod 4 being provided on the inside of the casing with a cross head 6 adapted to ride on two bars 7 supported in the front and rear walls of the casing, while springs 8 encircle the bars 7 and bear on the cross head for retracting the rod 4. The latter is normally held in extended position so as to place the springs 8 under compression and to project from the front wall of the casing by means of a trigger 9 pivoted to the front wall, as shown at 10, and having one end 11 engage in a notch 12 in the rod 4, the end 11 being preferably tapered for this purpose. The other arm 13 of the trigger is guided by a suitable clip 14 and has a pin 15 extending therefrom, which latter may be acted on by a revolvably-mounted arm 16 for releasing the rod 4. The arm 16 is mounted on a shaft 17 supported in the front wall and in two spaced brackets 18 depending from the top 19 of the case. A clock spring 20 has its inner end fastened to the shaft 17 and its outer end to a short parallel shaft 21 supported in the two brackets 18. Associated with the spring is a conventional clock mechanism, including a ratchet 22 fastened on the shaft 17, a cog wheel 23 loose on the shaft and adapted to be driven by the ratchet 22 by means of a pawl 24, a pinion 25 mounted on another shaft 26 and meshing with the cog wheel 23 and having a second cog wheel 27 fastened thereto, which latter has an escapement device 28 associated therewith.

The escapement device is mounted on a shaft 29, which has an arm 30 extending therefrom, and this arm may be held against

movement by means of a rod 31 slidably mounted in the front and rear walls of the case. This rod 31 is looped at one end, as shown at 32, and is fastened by means of a cord 33 to any suitable point of the airplane so as to be withdrawn from the casing when the person using the parachute jumps from the airplane.

The operation of the device will be readily understood from the foregoing description.

- 10 To set the watch spring 20, the operator, after inserting the rod 31, turns the arm 16 in a counterclockwise direction, the ratchet 22 turning with the shaft, but leaving the rest of the mechanism unaffected, since the pawl 23 slides over the teeth of the ratchet. The end of the rod 31 is fastened to a suitable point on the airplane and the end of the rod 4 is fastened to the rip cord of the parachute.
- 15 20 When the pilot or passenger carrying the parachute jumps off the airplane, the rod 31, which is fastened to the airplane, is automatically withdrawn and allows the clock mechanism to begin to operate. The arm 16 has been set in such a manner that the required number of seconds will elapse until it strikes the pin 15. When it does strike the latter pin, it causes the trigger 9 to release the rod 4, which is immediately retracted under the influence of the springs 8 and thereby pulls the rip cord for opening the parachute.

It will be noted that this arrangement works entirely automatically and does not require any act on the part of the person using the parachute.

35 The number of seconds that should elapse before the parachute opens may be exactly determined and the clock mechanism set so that the parachute will open at the predetermined time.

40 I claim:

1. An automatic time release for a parachute having a rip cord or the like for releasing the same comprising a case adapted to be fastened to the parachute, a rod slidably in a wall of the casing adapted for fastening to the rip cord, two guide bars in said casing, a cross head on the rod slidably on the bars, 45 springs guided by said bars and active on the cross head, a trigger on the outside of the casing adapted for engagement with the rod for holding the same in extended position while the springs are compressed, a revolvable arm adapted to actuate the trigger for releasing the rod, a clock mechanism for operating the arm, a second rod extending into the clock mechanism for preventing operation thereof, and means for fastening the second 50 rod to a relatively fixed body whereby the latter rod is withdrawn when the parachute moves relative to said body.

55 60 65 2. An automatic time release for a parachute having a rip cord or the like for releasing the same comprising a casing adapt-

ed to be fastened to the parachute, a rod slidably in a wall of the casing and adapted for fastening to the rip cord, two guide bars in the casing, a crosshead on the rod slidably on the bars, springs guided by said bars and active on the crosshead, means for holding the rod in extended position while the springs are compressed and a clock mechanism for releasing said means at the end of a predetermined period.

70 75 80 85 90 95 100 105 110 115 120 125 130 3. An automatic time release for a parachute having a rip cord or the like for releasing the same comprising a casing adapted to be fastened to the parachute, a rod slidably in a wall of the casing and adapted for fastening to the rip cord, spring means urging the rod to draw the rip cord, a trigger on the outside of the casing adapted for engagement with the rod for holding the same in extended position while the springs are compressed, a revolvable arm adapted to actuate the trigger for releasing the rod and a clock mechanism for operating the arm.

BENJAMIN F. TOFFLEMIRE.
